UNITED STATES PATENT OFFICE.

JAMES T. BOYD, OF INDIANAPOLIS, INDIANA.

COMBINED FRACTURE-BED AND INVALID'S CHAIR.

No. 823,841.

Specification of Letters Patent.

Patented June 19, 1906.

Application filed November 6, 1905. Serial No. 285,960.

To all whom it may concern:

Be it known that I, JAMES T. BOYD, a citizen of the United States, residing at Indianapolis, in the county of Marion and State of Indiana, have invented new and useful Improvements in a Combined Fracture-Bed and Invalid's Chair; and I do declare the following to be a full, clear, and exact description of the invention, reference being had to the accompanying drawings, and to the characters of reference marked thereon, which form a part of this specification.

This invention relates to articles that are designed to be used either as beds or chairs by persons who may have suffered fractures of bones or by invalids, the invention having particular reference to articles of this character that may be adjusted to suit the limbs of different persons which may be different in length either above or below the knees, the invention referring also to desk attachments of the combined bed and chair above mentioned.

Objects of the invention are to provide a combined fracture-bed and invalid's chair that may be adapted for both special and general use in offices of physicians or surgeons, in hospitals, or in dwellings; to provide an adjustable support for one having a fracture or fractures, which support may be instantly changed from a sitting position to a reclining position, or vice versa; to provide a fracture-bed with convenient adjustable foot-supports for the patient, adapted to either support the feet or to be used to stretch or extend the limb-muscles or to prevent contraction of the muscles, and to provide a combined desk and receptacle that may be supported adjustably in positions convenient to the patient or invalid.

With the above-mentioned and minor objects in view the invention consists in a combined fracture-bed and invalid's chair having rockers formed as arcs or segments of circles and provided with rollers, the bed and chair having an adjustable support for the knees of the occupant, an adjustable support for the lower limbs, and movable and adjustable foot-supports; and the invention consists, further, in the novel elements of construction and in the combinations and arrangements of elements, as hereinafter particularly described, and pointed out in the appended claims.

Referring to the drawings, Figure 1 represents a side elevation of the combined frac-

ture-bed and invalid's chair in upright position, including the adjustable desk thereof; Fig. 2, a front elevation thereof; Fig. 3, a central longitudinal vertical sectional view 60 thereof; Fig. 4, a rear elevation of the combined bed and chair in reclining position without the desk; Fig. 5, a fragmentary top plan and sectional detail view of parts of the adjustable knee-support; Fig. 6, a fragmentary sectional detail view of the movable support for the foot-plates, and Fig. 7 a top plan of the desk detached from its supports.

Similar reference characters in the different figures of the drawings designate corresponding elements or features.

In a practical embodiment of the invention the apparatus includes a main frame that comprises a pair of curved rockers A and A', that are preferably formed as arcs or segments of circles and employed in inverted positions or so that the peripheral portions may be on the ground while the ends of the segments extend upwardly, the middle portions of the rockers having rollers B and B' mounted thereon, and seat-rails C and C' and back-posts D and D' are attached to the ends of the rockers as parts of the main frame, a seat-rail and a back-rail being formed integrally of a single piece having a curved part 85 a, joining the two other parts together. When a seat-rail is horizontal, the connecting back-post is inclined in position. A pair of side bars E and E' are secured to the forward ends of the rockers and seat-rails and extend 90 obliquely to the upper end portions of the back-posts, to which they are secured, forming parts also of the main frame, which has legs b between the seat-rails and the rockers, legs b' between the parts a and the rockers, 95 and legs c between the back-posts and the rockers, there being X-braces d and e connecting the two sides of the main frame together, with clear spaces between the two seat-rails and also between the lower portions of the two back-posts, the X-braces being fixed parts of the main frame, another part of which is a headboard f, attached to the ends of the back-posts. The side bars E and E' each have a set of notches g in the middle portions and a set of notches h in the lower portions of the uppermost edges thereof for supporting the desk. A rod i is connected to the back-posts D and D' near the headboard f. A prop F is pivoted to the rod 110 i for use when the apparatus is tilted back as a bed.

A head-block *j* is supported on the forward end of each seat-rail, and a tail-block *k* is supported on the rail *C* or *C'* at a suitable distance from the head-block, there being screws 5 *G* and *G'* journaled in the head-blocks and engaging the tail-blocks, each screw being provided with an operating-crank *l* adjacent to the head-block. A suitable number of pegs *m* are attached to the tops of the side 10 rails *C* and *C'*, posts *D* and *D'*, and parts *a*, the pegs extending in rows from the tail-blocks *k* nearly to the tops of the back-posts at short distances apart. A pair of journal-boxes *H* and *H'* are mounted slidingly on the seat- 15 rails *C* and *C'* and support a roller *I*, that is journaled therein, the screws extending through the journal-boxes, which are suitably threaded so that they may be moved and controlled by the screws. A pair of frame- 20 bars *J* and *J'* are pivoted to the journal of the roller *I* adjacent to the journal-boxes *H* and *H'* and extend forwardly and downwardly beyond the forward ends of the seat-rails, the upper ends of the bars being consequently 25 movable with the roller and the journal-boxes, and the lower ends of the bars have curved braces *K* and *K'* pivoted thereto, that have bolt-holes *n* therein to receive bolts *p*, whereby the braces are adjustably attached 30 to the rockers *A* and *A'*, the bolts having thumb-nuts *q* thereon.

A winding-drum *L*, having a ratchet-wheel *M* secured thereto, is journaled between the lower ends of the bars *J* and *J'*, the ratchet-wheel being provided with a pawl *r*, whereby 35 to hold the drum, the drum being provided with a crank *s* for its operation. Preferably the pawl is mounted on a rod *t*, that extends between the two bars *J* and *J'*. A foot-rail *N* is mounted slidingly on the bars *J* and *J'* and supports foot-plates *O* and *O'*, having 40 slots *u* therein, through which straps may be extended for holding the plates against the feet of a patient. The foot-rail has clamp-plates *v* at its ends, that extend under and 45 against the bars *J* and *J'*, and a bolt *w* and thumb-nut *x* are provided for binding the foot-rail to the bars by means of the clamp-plates. When the thumb-nuts are slackened, 50 the foot-rail may be moved, and it may be drawn toward the drum *L* by means of cables *y*, that are connected with the foot-rail and wound about the drum.

A combined seat and back *P* is formed of 55 flexible material, such as canvas, and serves also as a support for the lower parts of the limbs of the patient, the seat portion of the element extending over the roller *I* and beyond, as a leg-support, a suitable distance be- 60 tween the bars *J* and *J'*, a lacing *8* connecting the upper end of the back to the rod *i* and lacings *9* connecting the sides of the seat and back to the pegs *m*, there being a lacing *10* connecting the lower end of the leg-support 65 to the rod *t*. The seat part has an apron *Q*

attached to the under side thereof and is free at one end thereof to drop downwardly, and the free end of the apron may be hung up to pegs *11*, that are attached to the back-posts *D* and *D'* by means of cords *12*, that are attached to the apron, there being an aperture *13* in the seat part of the member *P* above the apron, that may be a convenience to helpless invalids.

The desk *R* may be variously constructed 75 in detail, there being one or more receptacles therein and one or more lids *S* hinged on the top thereof, each lid having a knob *14* and a fastener *15*. The desk is provided with a pair of pivotal supports *T* and *T'* at its rear 80 end, adapted to be inserted in the notches *g* of the side bars *E* and *E'*, and a pair of pivots *U* and *U'* are attached to the forward end of the desk, to which a pair of curved props *V* and *V'* are connected, that have studs *W* and 85 *W'* attached thereto, adapted to be inserted into the notches *h* of the side bars, so that the desk may be removed from the side bars, or it may be propped up in inclined position, as indicated in broken lines in Fig. 1, to hold 90 books thereon or for like purposes.

In practical use the apparatus may be moved about on a floor by means of its rollers *B* and *B'*, it may be placed uprightly, as in Figs. 1, 2, and 3, for the sitting posture, or it 95 may be tilted rearwardly to form a bed, as in Fig. 4, so that the rollers would bear upon the floor forwardly of the parts of the rockers that may bear on the floor, and the prop *F* is to be adjusted so as to bear upon the floor and 100 support the head part of the bed so arranged, or the apparatus may be rolled over sufficiently to prevent the rollers from having contact with the floor, and therefore be supported by the rockers and the prop. When 105 a patient having a fracture is placed upon the combined seat and back *P*, the roller *I* should be adjusted so that the knees may be properly supported thereby, in some cases it being desirable to move the roller forwardly sufficiently to extend the large muscles somewhat. The patient's feet are to be placed upon the foot-plates *O* and *O'*, while the foot-rail *N* may be secured fixedly, or the latter 115 may be rendered movable and the feet may be bound to the foot-plates, so that the limbs below the knees may be slightly stretched or the muscles thereof extended to suit the conditions of the fracture. The roller *I* and the lower ends of the frame-bars *J* and *J'* may be 120 adjusted to contribute to the comfort of an invalid, and the combined seat and back may be rendered more or less flexible by adjustments of the supporting-lacings thereof.

Having thus described the invention, what 125 is claimed as new is—

1. A combined bed and chair including a main frame comprising a pair of rockers each provided with a roller approximately at the middle thereof, a pair of combined seat-rails 130

and back-posts attached to the ends of the rockers, an adjustable foot-plate frame, and a flexible combined seat and back supported adjustably by the main frame and the foot-plate frame.

5 2. A combined bed and chair including a pair of seat-rails and supports therefor, a pair of back-posts suitably supported, a pair of journal-boxes mounted movably on the seat-rails, means for moving and controlling the journal-boxes, a roller mounted in the journal-boxes, a foot-plate frame pivotally connected to the journal-boxes, and a flexible combined seat and back supported by the seat-rails and back-posts and extending over the roller and connected with the foot-plate frame.

20 3. A combined bed and chair including a main frame, a seat and back supported by the main frame, a foot-plate frame connected with the main frame and provided with a winding-drum, a pair of foot-plates mounted movably on the foot-plate frame and provided with cables connected therewith and attached to the winding-drum, and braces connecting the foot-plate frame adjustably with the main frame.

25 4. A combined bed and chair including a pair of seat-rails and supports therefor, a pair of back-posts suitably supported, a foot-plate frame mounted on adjustable pivots and provided with end supports, means for adjusting the pivots, a flexible combined seat and back supported by the seat-rails and back-posts and connected with the foot-plate frame, and a roller mounted adjustably under and partially supporting the seat part of the combined seat and back.

30 5. A combined bed and chair including a pair of seat-rails and supports therefor, a pair of back-posts suitably supported, a pair of journal-boxes supported adjustably, a roller mounted in the journal-boxes, a foot-plate frame pivoted at the journal-boxes and axis of the roller and adjustable therewith, means for adjusting and controlling the journal-boxes, supports connected to the free end of the foot-plate frame, and a flexible combined seat and back supported by the seat- 45 rails and back-posts and extending over the roller and connected with the foot-plate frame.

50 6. A combined bed and chair including a main frame having a seat and a back, a foot-plate frame connected to the main frame,

55 braces connecting the end of the foot-plate frame with the main frame, a foot-rail mounted slidingly on the foot-plate frame and having a pair of foot-plates secured thereto, means for binding the foot-rail to the foot-plate frame, and means for altering the position of the forward end of the seat with respect to the back.

7. A combined fracture-bed and invalid's chair including a main frame having a pair of rockers provided each with a roller, a pair of seat-rails and back-posts secured to the rockers, a pair of side bars secured to the seat-rails and also to the back-posts, and X-braces connected with the two sides of the main frame; a prop pivoted to the back-posts, a pair of journal-boxes mounted movably on the side rails, a roller mounted in the journal-boxes, a pair of screws mounted on the side rails and controlling the journal-boxes, a foot-plate frame pivotally connected with the journal-boxes and provided with a winding-drum having a ratchet-and-pawl lock, a pair of foot-plates mounted movably on the foot-plate frame and provided with cables connected to the winding-drum, a flexible combined seat and back mounted on the main frame and extending over the roller and connected with the foot-plate frame, and a desk mounted removably and 80 adjustably on the pair of side bars of the main frame.

8. In a combined bed and chair, the combination of a main frame having a pair of rockers, a pair of seat-rails and back-posts provided with pegs and secured to the ends of the rockers, and X-braces connected to the two sides of the main frame, a pair of journal-boxes supported adjustably and suitably guided, a roller mounted in the journal-boxes, a pair of screws suitably supported and controlling the journal-boxes, a foot-plate frame pivotally connected with the journal-boxes and provided with an end support, a pair of foot-plates mounted adjustably on the foot-plate frame, and a flexible combined seat and back connected with the pegs and also with the foot-plate frame and extending over the roller.

90 In testimony whereof I affix my signature 105 in presence of two witnesses.

JAMES T. BOYD.
